TANK TRAILER

Charles E. Mendez, Tampa, Fla., assignor to Redwing
Carriers, Inc., Tampa, Fla., a corporation of Florida

Filed Dec. 15, 1966, Ser. No. 5,060

Term of patent 14 years

(Cl. D14—3)

The dominant features of my design reside in the portions shown in full lines.

I claim:

The ornamental design for a tank trailer, substantially as shown and described.
